TUBE CLOSURE

Cedric B. Cooper, Vancouver, British Columbia,
Canada

Application December 11, 1946, Serial No. 715,572

7 Claims. (Cl. 220—30.5)

1

This invention relates to improvements in closures for tubes of the type used for shaving cream, tooth paste, and other plastic materials.

This invention is particularly designed for tooth paste and shaving cream tubes which are in constant use. At present, the difficulty is that when the tops or closures of these tubes are removed, they have to be placed on something. This often results in their loss altogether or they are forgotten and the contents of the tubes left exposed to the air for some time. Also, they are frequently dropped, causing much inconvenience and loss of time.

The main purpose of this invention is to provide a closure for tubes of this nature which will remain on the tube after it has been removed from the neck of the latter, which does not cause any inconvenience or delay to the user, and which will not add materially to the cost of manufacturing the tubes.

With the above and other objects in view, the present invention consists essentially of a closure for tubes having a neck, comprising a cap adapted to fit over the neck, means for raising the cap to the top of the neck, and means for receiving the cap on reaching the top of the neck when it is free therefrom, as more fully described in the following specification and illustrated in the accompanying drawing, in which

Figures 1 to 4 show one form of the invention, with the cap in different positions.

Figure 5 is an enlarged vertical section through the cap and tube neck,

Figure 6 is a perspective view of an alternative form of the invention,

Figures 7 and 8 show another alternative, and

Figure 9 is an elevation of the cap shown in Figures 7 and 8.

Referring more particularly to Figures 1 to 5, 10 is a tube having the usual neck 11 and 12 is a cap adapted to fit over said neck. Suitable means is provided for raising the cap to the top of the neck in less than one revolution. One way of accomplishing this is to provide the neck and the cap with co-operating threads, and Figures 3 and 5 clearly illustrate this. The neck 11 is formed with spaced spiral threads 15 and 16 extending approximately half way therearound, and the cap is formed internally with co-operating spaced spiral threads 17 and 18. All these threads preferably are rectangular in cross section, and the threads 15 and 16 have horizontal upper ends 19 spaced below the top of the neck, while the threads 17 and 18, which also extend approximately half way around the cap, have horizontal

lower ends 20 spaced above its lower edge. In Figure 1, the wall of the cap has been broken away to show its threads.

When the cap is normally on the neck, as shown in Figure 1, its internal threads engage the neck threads to prevent vertical displacement thereof, and when the cap is turned in the right direction, the threads 17 and 18 ride up the threads 15 and 16 until the ends 20 of the former are in line with the upper ends 19 of the latter, at which time the cap will not rise any further as it is rotated. When in this uppermost position, the cap is rotated horizontally to move the ends 20 on to the ends 19. This action takes place 15 while the cap moves through less than one complete revolution.

The cap 12 is formed with a lug 20 projecting from one side thereof and this lug carries a pin 21 extending outwardly therefrom adjacent its lower edge. A vertical support 22 is mounted on top of the tube adjacent the neck 11 and has a hole 23 formed therein preferably near its inner upper corner. This hole is arranged so that when the thread ends 20 of the cap ride on the thread ends 19, the pin 21 will enter said hole as the cap is rotated, see Figure 2. In Figures 1 to 4, a guard 24 is mounted on top of the tube spaced from the support 22. This guard has a guide bevel 25 at the upper end thereof. The guard 24 is shorter than the support 22 so that when the cap is moved into its uppermost position on the neck, the lower edge of the lug 20 just clears the guard but said lug engages the support.

At the moment the threads of the cap clear the neck threads, the pin 21 is just at the entrance of the hole 23, and when the cap is rotated further, the ends 20 ride in the ends 19 and the pin enters the hole. The cap is then free on the neck and may be pivoted back on the support, as shown in Figure 3. At this time, the lug enters the space between the support and the guard so that the latter prevents the pin from being withdrawn from the hole. In this way, the cap is carried by the support and it is clear of the tube neck.

Thus, to open the tube, it is only necessary to rotate the cap until its lug engages the support and then to pivot the cap away from the neck. To close the tube, the cap is pivoted back on to the neck and then rotated in the opposite direction to the first rotation until it is in its lowermost position.

In Figure 6, the guard 24 is omitted and a guard 26 is mounted on the lug 20 parallel with

2

and spaced from the latter and from the support 33. The cap is removed and replaced in this alternative as described above, but when it is pivoted away from the neck, the guard and the lug overlap the support, one on each side thereof, so that the pin 31 cannot be withdrawn from the hole 34 of the support.

Figures 7, 8 and 9 show an alternative in which the vertical support 33 is formed with an elongated hole 40 and the pin 31 of the lug 30 has a corresponding guard or key 41 on its outer end. When the cap 12 is rotated in its uppermost position, the guard or key 41 passes through the support hole 40, leaving the pin 31 therein, and when the cap is pivoted away from the neck 11, the guard or key lies across the hole, see Figure 8, so that the pin 31 cannot be withdrawn therefrom. The cap is replaced on the neck as described above.

What I claim as my invention is:

1. A closure for tubes having a neck, comprising a cap adapted to fit over the neck, means for raising the cap to the top of the neck, a lug projecting outwardly from the cap, a vertical support fixedly mounted on the top of the tube adjacent the neck, and means on the lug for engaging the support when the cap reaches the top of the neck when it is free of the latter, said cap being adapted to be pivoted on the support away from the neck.

2. A closure for tubes having a neck, comprising a cap adapted to fit over the neck, co-operating threads on the neck and in the cap for raising the latter on rotation to the top of the former, a lug projecting outwardly from the cap, a vertical support fixedly mounted on the top of the tube adjacent the neck, and a pin on the lug for engaging the support when the cap reaches the top of the neck when it is free of the latter, said cap being adapted to be pivoted on the support away from the neck.

3. A closure for tubes having a neck, comprising a cap adapted to fit over the neck, co-operating threads on the neck and in the cap for raising the latter on rotation to the top of the former, a lug projecting outwardly from the cap, a vertical support fixedly mounted on the top of the tube adjacent the neck, said support having a hole formed therein, a pin extending outwardly from the side of the lug positioned to be in line with the support hole when the cap reaches the top of the neck when it is free of the latter, said cap being adapted to be pivoted on its pin away from the neck after said pin is moved into the hole.

4. A closure for tubes having a neck, comprising a cap adapted to fit over the neck, co-operating threads on the neck and in the cap for raising the latter on rotation to the top of the former, a lug projecting outwardly from the cap, a vertical support fixedly mounted on the top of the tube adjacent the neck, said support having a hole formed therein, a pin on the lug which enters the

support hole when the cap reaches the top of the neck when it is free of the latter and the lug is moved against the side of the support, and a guard adapted to co-operate with the lug and support, said guard preventing the pin from being withdrawn from the hole when the cap is pivoted on said pin away from the neck.

5. A closure for tubes having a neck, comprising a cap adapted to fit over the neck, co-operating threads on the neck and in the cap for raising the latter on rotation to the top of the former, a lug projecting outwardly from the cap, a vertical support fixedly mounted on the top of the tube adjacent the neck, said support having a hole formed therein, a pin on the lug which enters the support hole when the cap reaches the top of the neck when it is free of the latter and the lug is moved against the side of the support, and a guard mounted on the top of the tube spaced from the support, said guard being shorter than the support, and the lug moving between the guard and support when the cap is pivoted away from the neck.

6. A closure for tubes having a neck, comprising a cap adapted to fit over the neck, co-operating threads on the neck and in the cap for raising the latter on rotation to the top of the former, a lug projecting outwardly from the cap, a vertical support fixedly mounted on the top of the tube adjacent the neck, said support having a hole formed therein, a pin on the lug which enters the support hole when the cap reaches the top of the neck when it is free of the latter and the lug is moved against the side of the support, a guard mounted on the lug and spaced therefrom, the lug and guard overlapping the support when the cap is pivoted away from the neck.

7. A closure for tubes having a neck, comprising a cap adapted to fit over the neck, co-operating threads on the neck and in the cap for raising the latter on rotation to the top of the former, a lug projecting outwardly from the cap, a vertical support mounted on the top of the tube adjacent the neck, said support having an elongated hole formed therein, a pin on the lug, a key on the outer end of the pin which passes through the support hole when the cap reaches the top of the neck when it is free of the latter, said key retaining the cap on the support when it is pivoted away from the neck.
